UNITED STATES PATENT OFFICE.

MARSHALL J. PAYNE, OF STAUNTON, VIRGINIA.

VALVE.

1,223,901.

Specification of Letters Patent. Patented Apr. 24, 1917.

Application filed July 26, 1916. Serial No. 111,448.

To all whom it may concern:

Be it known that I, MARSHALL J. PAYNE, a citizen of the United States, and resident of Staunton, in the county of Augusta, and in the State of Virginia, have invented a certain new and useful Improvement in Valves, and do hereby declare that the following is a full, clear, and exact description thereof.

10 My invention relates to valves, such as those used for containers for liquids, gases and air in which the internal pressure on the valve is utilized to hold it to its seat, and the object of my invention is to provide a

15 valve of this description which is held normally into contact with its seat and which may be positively held upon its seat regardless of the effect of any spring mechanism and regardless of the internal pressure. The

20 device is exceedingly simple, its parts will be few, and its operation may be performed without any special skill or knowledge on the part of the operator, and it is, therefore, well adapted to the purpose for which it is

25 intended.

Figure 1 is a vertical section of the valve embodying one form of my invention.

Fig. 2 is a horizontal section of Fig. 1.

In Fig. 1 of the drawing, the valve casing 30 3 having the hexagonal part 5 shown is of any suitable material and form constructed so that the casing 3 extends from within the container outward, and having a suitable valve seat 2 preferably integral with the casing and adapted to coöperate with the valve 1 on the inner end of the stem 4 extending through the tubular opening 4^a of the casing 3 and suitably fastened at 10 to the washer 9, said washer resting on sleeve 6.

40 The tubular sleeve 6 is shown having external screw threads, and adapted to engage the internally screw threaded cap or tap 11, said tap 11 resting on the upper surface of the hexagonal part 5. The spring 7 is shown in the recessed space 8 with one end resting on the shelf 7^a of the casing and having the other end in contact with the expanded nib 4^a on the stem 4. Upon the casing 3 is shown the projecting tubular extension 12 upon which is slidably mounted an externally threaded sleeve 6, said sleeve 6 while movable axially or longitudinally, is prevented from rotating or turning as by flattening or slabbing off the periphery of 55 the block extension 12 and conforming thereto the contiguous surface of the bore

or axial opening through the sleeve 6. The external threaded sleeve 6 is employed also in making connections for inflating or filling from pumps or containers.

In Fig. 2 is shown the tubular extension 12, having the flattened side 13 and the conforming side 14 of the sleeve 6 and the tap or cap 11 all in proper operative relation. In the recessed space 8 is shown the spring 65 7 and the valve stem 4 suitably placed or positioned.

The action of the device is easily understood by reference to the drawings, and is as follows:—

It is obvious that whenever the cap 11 is screwed upon the sleeve 6 and the inner end of the cap impinges against the hexagonal piece 5 the sleeve 6 will be moved axially since it is incapable of rotation. I employ 75 this outward movement of the sleeve 6 to positively move and hold the valve to its seat.

By unscrewing the dust cap 11 it is likewise well understood that movement of the sleeve may occur in the opposite direction and the valve may be put in position for inflating or filling by lifting the valve off its seat. I employ the spring 7 to keep or maintain the valve 1 normally into contact 80 with the valve seat 2, and in this way obviate the escape of air or any element in case the cap 11 is left off or not fully turned downward.

Claims:

1. A valve comprising a casing having an internal valve seat, a valve to coöperate with the seat having a valve stem extending through a channel longitudinal in the casing, said channel having a recessed space 95 opposite the valve seat, a spring in the recessed space bearing on the valve casing and the valve stem and acting to hold the valve to the seat; an externally threaded sleeve on the casing adapted for axial and not rotary movement, a threaded member engaging the said sleeve with means for moving and holding the valve to its seat.

2. A valve comprising a casing having an internal valve seat, a valve to coöperate with the seat having a valve stem extending through a channel longitudinal to the valve casing, a recessed space in the channel opposite the valve seat, a spring in the recessed space bearing on the valve casing and the valve stem, an externally threaded sleeve on the casing positioned for axial and not ro-

tary movement, said sleeve operatively connected to the valve stem, with means for moving and holding the valve to its seat, said means embracing the spring in the recessed space, a threaded member adapted to bear on the valve casing and acting to move the sleeve in an axial direction.

In testimony that I claim the foregoing I have hereunto set my hand.

MARSHALL J. PAYNE.
